US00D842152S

(12) **United States Design Patent** (10) Patent No.: **US D842,152 S**
(45) Date of Patent: **** Mar. 5, 2019**

(54) **SENSOR HOLDER**

(71) Applicant: **TELESONIC HOLDING AG,**
Bronschhofen (CH)

(72) Inventor: **Claus Regenberg**, Zirndorf (DE)

(73) Assignee: **TELSONIC HOLDING AG,**
Bronschhofen (CH)

(**) Term: **15 Years**

(21) Appl. No.: **35/504,099**

(22) Filed: **Oct. 12, 2017**

(80) **Hague Agreement Data**

Int. Filing Date: **Oct. 12, 2017**

Int. Reg. No.: **DM/098681**

Int. Reg. Date: **Oct. 12, 2017**

Int. Reg. Pub. Date: **Dec. 8, 2017**

(51) **LOC (11) Cl. 10-04**

(52) **U.S. Cl.**

USPC **D10/103**

(58) **Field of Classification Search**

USPC D13/103, 112; D10/104.1, 121, 103

CPC B62D 15/02; G03B 3/02; H04N 5/2257;
G01D 5/24433

See application file for complete search history.
